UNITED STATES PATENT OFFICE.

SAMUEL B. STEWART, JR., OF SCHENECTADY, NEW YORK, ASSIGNOR TO GENERAL ELECTRIC COMPANY, A CORPORATION OF NEW YORK.

PANTOGRAPH-TROLLEY.

1,098,133.

Specification of Letters Patent. Patented May 26, 1914.

Application filed September 10, 1908. Serial No. 452,412.

To all whom it may concern:

Be it known that I, SAMUEL B. STEWART, Jr., a citizen of the United States, residing at Schenectady, county of Schenectady, 5 State of New York, have invented certain new and useful Improvements in Pantograph-Trolleys, of which the following is a specification.

This invention relates to current-collecting devices for electric railway cars, and its 10 object is to enable the traveling contact to respond more readily to irregularities in the trolley wire.

When a car is running at a speed of 15 forty miles an hour, or more, the trolley is unable to follow accurately the vertical variations of the trolley wire owing to the inertia of the somewhat cumbersome trolley structure which imposes a certain sluggishness or lag upon its movements. Even with 20 the catenary method of suspension there are still some places where the wire is higher than at other places, and if the trolley jumps off it entails arcing, trouble and delay. My 25 invention remedies these difficulties by providing a supplemental mounting for the contact proper, so that it can have a certain range of play independent of the trolley structure, whereby, owing to the comparative 30 lightness of the traveling contact, it will more readily and quickly adapt itself to variations in the stationary conductor.

The invention is capable of development in many different designs, some of which are 35 shown in the accompanying drawing, in which—

Figure 1 is a side elevation of a pantograph trolley embodying one form of my invention; Fig. 2 is a top plan view thereof, and Figs. 3 and 4 show modified modes 40 of mounting the traveling contact.

High speed electric locomotives are nowadays usually provided with pantograph trolleys, and I have therefore illustrated 45 the application of my invention to such a structure, comprising toggle-arms or frame 1, 2 carrying a transverse sliding collecting shoe or pan 3, or a rotating collector 3'. The upper ends of the upper members 2 of 50 the toggles can be variously connected. In Figs. 1 and 2 they are pivoted to a short rigid bridge-piece 4, and the pan is hinged to the upper ends of short diverging levers 5 whose lower ends are pivoted to the bridge-piece, preferably by the same pivots 6 as the

arms 2. These pivots pass through slots in said levers so that said levers can slide thereon and thus separate or approach as may be necessary. These slots are preferably arranged lengthwise of the bent ends 7 of said levers. A tension spring 8 connects the lower ends of the levers and urges the pan upwardly. When the trolley is in running position in contact with a trolley wire, the pan will be somewhat depressed from the position in which it is shown being forced down until the tension of the spring 8 balances the upward thrust of the regular trolley-lifting springs (not shown). The pan will thus float in an intermediate position 70 with the pivots 6 about midway of the slots. Any sudden depression or elevation of the pan, due to a variation in the trolley wire, will be taken care of by the spring 8 which will yield quickly to a depression and contract quickly to follow up an elevation of the trolley wire. The lightness of the pan and its supporting levers, as compared with the weight of the entire trolley structure, 75 enables it to follow the wire very closely, and to a large extent independently of the movements of the somewhat cumbersome and slow-moving pantograph structure.

In lieu of the bridge-piece 4, I may cross the upper ends of the arms 2 and pivot 85 them together at 9, as shown in Fig. 3. In other respects, the device shown in this figure is the same as that in Fig. 1, except that a roller 3' is substituted for the sliding pan 3.

Fig. 4 shows the pan or equivalent traveling contact mounted on flat arched springs 10 instead of on pivoted levers. The arch 10 has horizontal ends supported in any suitable manner by the upper arms 2, preferably 90 on plates 11 pivoted to the arms, and either one or both ends of the arch has a horizontal slot 12 engaging with a headed pin 13 inserted in the plate. This permits the arch to flatten down when pressure is 95 brought to bear upon the traveling contact, said end sliding back and forth on the plates as the contact floats up and down in following the variations of the trolley wire. The tension of the spring arch of course increases 100 as it is flattened down, so that it will quickly assume a position corresponding with the upward thrust of the pantograph springs. By means of these or equivalent supplemental 105 mountings for the trolley pan, a 110

trolley is produced which will closely follow the undulations of the trolley-wire at modern railway speeds.

What I claim as new and desire to secure 5 by Letters Patent of the United States, is,

1. The combination with a pantograph trolley, of a transversely extending current collector, pairs of levers pivoted to the upper arms and supporting the current collector, and resilient means acting upon said levers for urging said collector directly upward.

2. The combination with a pantograph trolley, of levers pivoted to the traveling contact and to the upper arms of the trolley, and resilient connections attached to the lower ends of said levers.

3. The combination with a pantograph

trolley, of a pair of levers pivoted to the traveling contact and having slots engaging 20 pivots on the upper arms of the trolley, and a spring connecting said levers.

4. The combination with a pantograph trolley, of a bridge-piece pivoted to the upper arms thereof, a pair of levers pivoted to 25 the traveling contact and having bent ends containing slots engaging pivots on said bridge-piece, and a tension spring connecting the ends of said levers.

In witness whereof, I have hereunto set 30 my hand this 9th day of September, 1908.

SAMUEL B. STEWART, JR.
